ANTENNA

Harold O. Peterson, Riverhead, N. Y., assignor to
 Radio Corporation of America, a corporation of
 Delaware

Application May 19, 1936, Serial No. 80,498

8 Claims. (Cl. 250—33)

The present invention relates to antennas, and particularly to an antenna system for radiating horizontally polarized waves substantially equally in all directions in the horizontal plane.

5 The vertical antennas commonly used at transmitters for broadcasting purposes have the property of radiating vertically polarized waves substantially equally in all directions along the horizontal plane. It is in some cases found desirable 10 to radiate energy which is horizontally polarized, since a horizontally disposed receiving antenna will in many cases be less susceptible to local interference than one oriented for the reception of vertically polarized waves. It is, however, not 15 possible to broadcast horizontally polarized waves in all directions with the horizontal type of doublet antenna commonly used, inasmuch as these have a directive characteristic whereby they radiate very little energy in a direction parallel 20 to the length of the doublet. The present invention provides an efficient antenna system which radiates horizontally polarized waves substantially equally in all directions.

25 Referring to the drawing, Figs. 1, 2, 3, 4, 5 and 6 illustrate, diagrammatically, transmitting antennas in accordance with the invention, for producing radiation of horizontal polarization with equal efficiency in all directions. Figs. 4a and 4b are given to illustrate the distribution of 30 current amplitude on the two halves of the system of Fig. 4 at any instant.

35 Fig. 1 shows an antenna comprising a conductor 1 arranged in the form of a circle in the horizontal plane and having a diameter equal to

$$\frac{2\lambda}{\pi}$$

40 where λ is the wavelength. In other words, the diameter shown in Fig. 1 is such that the circumference is approximately two wavelengths long. If the circumference is chosen to be an even integer number of wavelengths long, such circumference must be used that will produce a diameter close enough to an odd number of half 45 wavelengths, so as to produce substantially equal radiation in the horizontal plane. Similarly, if the circumference is chosen to be an odd integer number of wavelengths long, such circumference must be used that will produce a diameter close 50 enough to an even number of half wavelengths to achieve the same result. In other words, suitable lengths must be chosen to satisfy the above relationship of circumference and diameter. These lengths in many cases will not be integral 55 multiples of wavelengths or half wavelengths but

will vary therefrom, although substantially obeying the laws set forth above. This relationship is required to be such that the radiation fields from current elements in opposite sides of the circumference add up in phase at a distance. 5 In the case of Fig. 1, this condition is satisfied for radiation in directions inclined 38° from the plane of the loop. In other words, optimum radiation for the system of Fig. 1 is at an angle of 38° from the plane of the loop. It should be 10 understood, however, that although optimum radiation is at an angle to the plane of the loop in the system of Fig. 1, that the waves are radiated substantially equally in all directions in the 15 plane of the loop. For optimum radiation in the plane of the loop it would be necessary to modify the dimensions of Fig. 1 so that the diameter is 0.88 λ .

This value is derived as follows for optimum 20 radiation in the plane of the loop: Let

$$\frac{360^\circ \cdot \pi \cdot R}{\lambda} - 180^\circ = \frac{360^\circ \cdot 2 \cdot R}{\lambda}$$

wherein the term

$$\frac{360^\circ \cdot \pi \cdot R}{\lambda}$$

represents the degrees of phase delay experienced by an increment of current in traveling through one-half of the circumference of the loop, R being 30 the radius of the loop.

The term 180° is introduced by the fact that an increment of current traveling forward through the conductor will, relative to outside space, travel in opposite directions when passing 35 through two diametrically opposite points in the loop.

The term

$$\frac{360^\circ \cdot 2 \cdot R}{\lambda}$$

represents the phase delay in degrees, of the space wave in traveling across the diameter of the loop.

This equation reduces to $R = .44\lambda$. The energy 45 from the transmitter T, here shown conventionally, is fed through a radiationless type of transmission line T'L' into this circular shaped conductor at one end, and the other end of the conductor is damped by means of surge resistance R so that flow of energy along the conductor is in one direction only, and consequently no standing waves exist on the conductor. The current waves in the conductor travel in the direction indicated by the arrow. The effect of this traveling current wave on the wire is to produce 50 55

instantaneously maximum radiation in certain directions and minimum radiations in other directions. However, the direction of maximum and minimum radiation changes as the current 5 wave progresses around the wire, resulting in substantially equal radiation of energy in all directions along the horizontal plane. The broken lines around the antenna 1 indicates the current 10 lines along the antenna 1 indicates the current amplitude distribution at a given instant.

10 Fig. 2 illustrates a modification of this type of radiator in which a cylindrical reflector 2 is placed inside of the circle and spaced from the conductor by a suitable amount sufficient to give reflection of proper phase. For this condition, 15 the antenna will be spaced approximately one-quarter wavelength from the reflector. Reflector 2 is preferably made of metal, although it may be made of a substance whose dielectric constant is considerably greater than that of air.

20 Fig. 3 shows, in cross section, a modification of this reflector wherein a circular antenna conductor 3 is placed between two annular reflectors 4, 4' which face one another and are designed, 25 in the manner shown, to give concentration of energy in the vertical plane. This system of this figure, as well as that of Fig. 2, may be energized in the same manner as that of Fig. 1 so as to preclude the formation of standing waves.

Fig. 4 shows a system utilizing two parallel 30 circles of conductors 5, 5' fed from a symmetrical and closely spaced transmission line TL and spaced apart by approximately one-half the length of the communication wave. The ends of transmission line TL are normally in phase 35 opposition. Since both of the parallel conductors extend in the same direction, it is therefore necessary to interpose a one-half wave section of line S in series with one side of the transmission line so that the currents in the two circular antennas will be cophasal. Another one-half wave 40 section of line S' is also applied at the far end of the system connecting the two halves together through surge resistor R. It should be understood that the total length of section S' including the length of damping resistance R is one-half wavelength.

45 Figs. 4a and 4b illustrate, respectively, the instantaneous current distribution by means of dotted lines along the upper and lower halves of the system of Fig. 4. It will be seen that the two circles 5 and 5' are excited cophasally and therefore aid each other in radiation along the horizontal plane. It will be understood, of course, that if desired any number of these sections may 50 be stacked one above the other, to obtain concentration of energy in the vertical plane.

55 Fig. 5 shows a modification in which energy is fed from a transmitter T, through a radiationless concentric type of transmission line T'L' into a spiral shaped conductor 6, thus obtaining the 60 effect of several circular radiators stacked one above the other to obtain concentration of radiation in the vertical plane. It is preferred that the turns of the spiral be spaced at least one-quarter wavelength apart to minimize mutual interaction between turns. Since each turn of the 65 spiral is two wavelengths long, the currents in the various turns will be cophasal, and the radiation effects will be cumulative in a plane perpendicular to the axis of the spiral. The vertical portion of the system of this figure is generally located within the spirals of the conductor 70 6.

75 Fig. 6 illustrates an arrangement in which the circular radiator 7 is located at such distance

above a reflecting earth as to produce substantial concentration of radiation at an angle α inclined considerably above the horizontal. The distance above ground should be such that at a 5 distance, the direct ray radiated from the antenna will be cophasal to the indirect ray which is reflected from the ground. For the geometry of Fig. 6, this condition is satisfied when the distance A, B, C is a half wavelength different from an integer number of wavelengths. It is thus 10 possible to produce a hollow cone-shaped directive diagram which is very desirable for some types of work as, for example, beacons for aiding the navigation of aircraft.

15 While the current distribution diagrams shown in dotted lines in Figs. 1, 4a and 4b suggest a circle having a circumference of two wavelengths, the system may obviously be constructed with parallel conductors of other lengths, chosen with discretion so as to have the proper radiation characteristics. For instance, the influence 20 which the various circles have upon each other in the stacked antennas shown in Figs. 4 and 5 may be such as to alter the phase velocity of the conductors, in which case the diameter will have to be so changed as to make one circumference 25 have an electrical length of two wavelengths.

It will be obvious, of course, that the antenna 30 of the invention may be used to radiate vertically polarized waves if the system is oriented such that the axis of the circular conductors is horizontal. If this were done, then maximum radiation would ordinarily be along a direction perpendicular to the axis of the circular conductor.

What is claimed is:

1. An antenna system for transmitting horizontally polarized waves comprising a radiating conductor in the form of a circle whose diameter is equal to

$$\frac{2\lambda}{\pi}$$

40

where λ is the length of the communication wave, said conductor having uniformly distributed inductance and capacitance and being located in the horizontal plane, and means for energizing 45 said conductor and preventing the formation of standing waves thereon.

2. An antenna system for transmitting horizontally polarized waves comprising a conductor in the horizontal plane in the form of a circle 50 and having two terminals, another similarly located conductor spaced from said first conductor in the vertical plane, means for serially connecting said conductors together for cophasal energization thereof including a damping impedance 55 coupling together one terminal of one conductor with the correspondingly located terminal of the other conductor, and a two-wire substantially radiationless transmission line one of whose wires is connected to the other terminal of said 60 one conductor and the other wire of which line is connected through a radiationless loop to the other terminal of said other conductor, the length of one side of said radiationless loop being a half wavelength.

3. An antenna system for transmitting horizontally polarized waves comprising a radiating conductor in the horizontal plane substantially in the form of a circle, said conductor having uniformly distributed inductance and capacitance, 70 and means for energizing said conductor and preventing the formation of standing waves thereon, the length of the circumference of said circle being substantially an even integer number of wavelengths, so chosen that the diameter is 75

approximately an odd number of half wavelengths, whereby radiation is substantially limited to the horizontal.

4. An antenna system for transmitting horizontally polarized waves comprising a radiating conductor in the horizontal plane substantially in the form of a circle, said conductor having uniformly distributed inductance and capacitance, and means for energizing said conductor and preventing the formation of standing waves thereon, the length of the circumference of said circle being substantially an odd integer number of wavelengths long, so chosen that the diameter is approximately an even number of half wavelengths, whereby radiation is substantially limited to the horizontal.

5. An antenna system comprising a plurality of substantially parallel radiating loops located substantially along an axis perpendicular to the planes of said loops, each of said loops having uniformly distributed inductance and capacitance and having a length substantially equal to an integer times the length of the communication wave, means for connecting said loops in electrically series relation with respect to one another, whereby the energy conductively flows through one loop to the next adjacent loop, and means for preventing the formation of standing waves in said loops.

30 6. An antenna system comprising a plurality of substantially parallel radiating loops located substantially along an axis perpendicular to the

planes of said loops, each of said loops having uniformly distributed inductance and capacitance and having a length substantially equal to an integer times the length of the communication wave, said radiating loops being spaced apart 5 from one another a distance equal at least to one-quarter the length of the communication wave, means for connecting said loops in electrical series relation with respect to one another, whereby the energy conductively flows through 10 one loop to the next adjacent loop, and means for preventing the formation of standing waves in said loops.

7. An antenna system in accordance with claim 2, characterized in this that said two conductors 15 are spaced approximately one-half wavelength apart.

8. An antenna system for radiating substantially horizontally polarized waves, comprising a plurality of radiating loops located above one 20 another and symmetrically with respect to an axis therethrough, each of said loops having uniformly distributed inductance and capacitance and having a length substantially equal to an integer times the length of the communication 25 wave, means for connecting said loops in electrically series relation with respect to one another, whereby the energy conductively flows through one loop to the next adjacent loop, and means for preventing the formation of standing 30 waves in said loops.
